John Young
ATTORNEY.

UNITED STATES PATENT OFFICE.

FREDERICK G. BEVANS, OF KANSAS CITY, MISSOURI, ASSIGNOR TO IRVING-PITT MANUFACTURING COMPANY, OF KANSAS CITY, MISSOURI, A CORPORATION OF MISSOURI.

LOOSE-LEAF BINDER.

Application filed September 11, 1926. Serial No. 134,878.

This invention relates to loose leaf binders and has particular reference to means carried within the binder and forming a part thereof for guiding the sheets of the binder 5 to a predetermined position along the sheet holding means as the binder covers are being closed.

One of the objects of my invention is to provide means which may be easily attached 10 to any standard make binder of the ring type, which is best adapted to perform its duties of guiding the sheets to the proper location after it has been placed in the binder.

Another object of the instant invention is 15 the provision of an extremely simple, efficient, effective and durable means for performing the duties of guiding loose leaf binder sheets to the proper position on the sheet holding means during the time the 20 binder is being closed.

It is well known in this art that ring binders, particularly of the larger size are objectionable in that when the binder is being closed, the sheets thereof will fall between 25 the rings and the covers, thus becoming bound in that position and precluding further movement of the covers toward a completely closed position.

Minor objects and specific details of construction will appear during the course of 30 the following specification, referring to the accompanying drawing, in which:

Figure 1 is a plan view of a loose leaf ring binder showing the same in the open position 35 and having therein means made in accordance with my invention for properly positioning the binder sheets when the binder is closed;

Fig. 2 is a fragmentary cross section taken 40 on line II—II of Figure 1;

Fig. 3 is a similar section with the binder moved to the partially closed position;

Fig. 4 is a similar section taken clear 45 through the binder showing the same in the completely closed position, sheets being held in the desired location by the novelly constructed fly leaves; and

Fig. 5 is a perspective view of a ring binder 50 fly leaf showing the same entirely removed from the binder and clearly illustrating the curled back margin formed along the bound edge thereof.

Similar reference characters refer to identical parts throughout the several views and 55 the numerals 6 and 7 respectively designate

the two covers of a loose leaf binder of the ordinary type, which as is customary carries the binder metal 8 therein, which includes rings 9 adapted to open and close when it is desired to place and remove the perforated 60 binder sheets 10.

To this point it is obvious that the structure set forth is old and no invention therein is claimed.

The combination with a binder of this general character of novelly constructed fly leaves 12 will force the binder sheets 10 to the desired position as shown in Fig. 4 when the covers 6 and 7 are closed.

One form of embodiment of my invention 70 is clearly shown in the accompanying drawing. The same may consist of a pair of fly leaves 12 held by rings 9 in the usual manner with sheets 10 positioned therebetween.

Along one edge of fly leaf 12 is affixed a reinforcing strip 13 which may be riveted or otherwise affixed to the leaf 12 and which is perforated as at 14, which perforations pass over the several rings 9 in assembling the device. Strip 13 should be wide enough to 75 bridge the hinged portion of covers 6 and 7 to preclude sagging on the part of the fly leaf or binder sheets along the bound edge. Strip 13 must be formed to present the curled back margin 15 which projects within the rings 80 when the fly leaves are in place. This curled back margin 15 of each of the two fly leaves 12 rests above the binder metal 8 as the edges thereof abut and rest along the upper face of metal 8.

When the binder is in the open position shown in Fig. 2, the sheets therein are held against sagging and in a position away from the hinge of the adjacent cover 6 or 7. As the binder covers are raised toward the closed position, as shown in Fig. 3, the edge of each fly leaf 12 along the curled back margin 15 will ride over binder metal 8 and on to the inner periphery of rings 9. As the covers are further urged to the closed position, this curled back margin 15 will ride upwardly 85 along the rings pushing the sheets 10 ahead of the covers 6 and 7 so that as the covers just mentioned approach the sides of the rings 9 the sheets 10 will positively be forced to a position where they will not be caught and bound. A fly leaf 12 having a reinforcing strip 13 curled as at 15 will lift and guide the 90 entire sheet capacity of a ring binder to a segment of the rings located at the top and 100 105 110

exactly between the covers 6 and 7. The degree of curvature of curled margin 15 will vary slightly with rings of various diameters and as a guide to this degree of curvature it has been found advisable to insure the fact that the edge of curled margin 15 which rides over metal 8 and rings 9 be disposed between the major plane of its supporting fly leaf 12 and the adjacent cover.

10. If desired, a part of this curled back margin 15 may be cut away to conserve metal and render the binder lighter, thus leaving two or more portions or lugs of the curled margin present to perform the duty above set forth.

15. Having thus described the preferred form of my invention, what I claim and desire to secure by Letters Patent is:

20. 1. In a ring binder of the character described, a pair of fly leaves carried by the rings of the binder, each having a curled back margin projecting within the rings, the edges of said fly leaves along the curled back margin abutting and engaging the binder metal when said binder is in the open position.

25. 2. In a loose leaf ring binder of the character described, a pair of fly leaves each having

a curled back margin projecting within the rings of said binder, the edge of each fly leaf along the curled back margin adapted to engage the inner periphery of said rings as the 30 binder is closed whereby the sheets of the binder held between said fly leaves are forced along the rings ahead of the binder covers as said covers approach the rings thereof.

3. A fly leaf for ring binders having a 35 curled back margin along the bound edge thereof, the free edge of said margin riding against a portion of the inner periphery of the binder rings as the binder is opened or closed.

4. A fly leaf for ring binders having a re- 40 inforcing strip integral therewith along one edge thereof, perforations formed through said strip for engaging the rings of said binder and a curled back margin formed between said perforations and edge having its free 45 edge engaged by a portion of the binder rings to support said fly leaf as the binder is opened or closed.

In testimony whereof, I have hereunto affixed my signature this 27th day of August, 50 1926.

FREDERICK G. BEVANS.
